UNITED STATES PATENT OFFICE.

JOHN ELIAS EVANS, OF SPANISH FORK, UTAH TERRITORY.

HARNESS-TUG HOOK.

SPECIFICATION forming part of Letters Patent No. 281,987, dated July 24, 1883.

Application filed May 11, 1883. (No model.)

To all whom it may concern:

Be it known that I, JOHN E. EVANS, of Spanish Fork, in the county and Territory of Utah, have invented a new and useful Improvement 5 in Harness-Tug Hooks, of which the following is a full, clear, and exact description.

The object of my invention is to furnish an improved device for securing tugs to single-trees—one that can be conveniently operated 10 and shall be safe and sure.

It consists in a hook having a pivoted tongue, the hook and tongue being formed for connection to the tug, and a spring provided for retaining the parts in position, all as hereinafter 15 described and claimed.

Reference is to be had to the accompanying drawings, forming a part of this specification, in which similar letters of reference indicate corresponding parts in all the figures.

20 Figure 1 is a face view, and Fig. 2 an edge view, of my tug-hook. Fig. 3 is a face view of the spring detached, and Fig. 4 is a view of the hook in an opened position.

a is the hook, and *b* the tongue, each formed 25 with an eye, *c*, at one end, and attached together in **X** form by a pin, *d*.

e is the bar for attachment of tug *f*, connected to a second bar, *g*, that passes through the eyes *c* of the hook *a* and tongue *b*, so that 30 they are free to turn thereon, and may slide inward, as shown in Fig. 4, when the hook is opened.

Between the outer ends of the hook and tongue is a **U**-shape spring, *h*, formed with

eyes at its ends, as shown in Fig. 3, for passing 35 upon the bar *g*, and also sitting into grooves formed in the hook and tongue ends, whereby the spring is held securely in place and exerts its power to press the eyes *c* apart, consequently holding the beveled end of the tongue 40 *b* against the beveled end of the hook. The end of the hook is made with lugs *i*, that lap into recesses formed in the end of tongue *b*, so as to cover the point and prevent its being caught by the single-tree ring when the tug is 45 slackened.

This tug-hook can be readily applied, and will hold securely without danger of becoming accidentally opened.

In place of using a flat spring, as shown, the 50 bar *g* may be fitted with a spiral spring.

Having thus described my invention, I claim as new and desire to secure by Letters Patent—

1. The tug-hook, consisting of hook portion *a* and tongue *b*, formed with eyes *c*, pivoted 55 together in **X** form, and fitted with a spring, substantially as described.

2. The combination of hook *a*, pivoted tongue *b*, eyes *c*, bar *g*, and spring *h*, substantially as described.

3. The spring *h*, formed with eyes at its ends, combined with the hook *a*, tongue *b*, and holding-bar *g*, substantially as described.

JOHN ELIAS EVANS.
